RAIL CLAMP

David Rich, Rice Lake, Wis.

Application March 30, 1942, Serial No. 436,873

2 Claims. (Cl. 254—43)

This invention relates to tie-spacing devices, and more particularly to an improvement on the device disclosed in my prior Patent No. 2,188,819, issued January 30, 1940.

It is an object of the invention to provide a rail clamp for securing the tie-spacing device to the head of a rail which is readily adjustable to secure a closer and tighter fit between the clamp and the rail head.

A further object of the invention resides in providing an adjustable rail clamp which is simple and durable in construction, reliable and efficient in operation, and inexpensive to manufacture.

Other objects and advantages of the invention will be apparent during the course of the following description.

In the accompanying drawing forming a part of this specification and in which like numerals are employed to designate like parts throughout the same,

Fig. 1 is a side elevational view of the tie-spacing device,

Fig. 2 is a top plan view of the rail clamp,

Fig. 3 is a side elevational view of the rail clamp,

Fig. 4 is an enlarged longitudinal sectional view taken on line 4—4 of Fig. 2,

Figs. 5, 6, 7, and 8 are fragmentary sectional views of the various sizes of shims employed with the rail clamp,

Fig. 9 is an enlarged fragmentary sectional view showing a modified form of adjustable shim for the rail clamp, and

Fig. 10 is a cross section taken on line 10—10 of Fig. 9.

In the drawing, wherein for the purpose of illustration I have shown a preferred embodiment of my invention, the tie-spacer includes an open rectangular frame 5 having a rock lever 6 pivotally mounted therein by a pivot bolt 7. The upper end of the rock lever extends above the frame and terminates in a socket 8 adapted to receive an operating bar 9. The lower end of the rock lever is bifurcated, as at 10, and extends below the frame to receive one end of a tie-engaging member 11 which is pivotally secured between the furcations by a pivot bolt 12. The member 11 adjacent its opposite end is provided with oppositely extending lugs 13 and 14 formed along its upper and lower edges, adapted to engage the side of the tie to be moved.

The foregoing construction is common to the device disclosed in my prior patent, and the present invention relates only to the rail clamp-

ing member for securing the frame 5 to the side of a rail head, as shown in Fig. 1. The rail clamp includes a laterally extending arm 15 connected to one side of the frame 5 by spaced webs 16 cast integral with the frame and arm. The under side of the arm 15 is recessed as at 17 to form inner and outer jaws 17' and 18' adapted to engage opposite sides of the head 18 of a rail 19. The outer jaw at its lower end has an inwardly projecting lip 20 adapted to engage beneath the under side of the rail head, and in order to facilitate the placing of the jaw over the rail head the inner side of the outer jaw is provided with a notch 21 above the lip which permits the clamp to be readily engaged over the rail head, as shown in dotted lines in Fig. 4. The inner jaw is provided with a recess 22 to receive the shims 23 which are of varying sizes, as shown in Figs. 5, 6, 7, and 8. The lower end of the shim is provided with a projecting lip 24 which engages beneath the under side of the rail head, and an opening 25 through the center of the shim is adapted to align with the aperture 26 through the inner jaw to receive a bolt 27 for securing the shim in fixed engagement with the recess 22. Thus it is seen the shims are readily interchangeable so that the space between the jaws may be readily adjusted to fit rail heads of various widths.

In Figs. 9 and 10 a slightly modified form of adjustable rail clamp is shown wherein the inner end 28 of the arm 15 is disposed at an angle of approximately 20° to the head of the rail. The inner jaw 29 of the clamp is formed integral with the under side of the inner end 28 of the arm 15 and has an elongated socket 30 formed in its face adapted to slidably receive a shim block 31 having a central screw-threaded bore 32 in its inner end. An adjusting bolt 33 extends through an aperture 34 through the inner jaw 29 and threadedly engages the bore 32 of the shim block. A retaining washer 35 is mounted on the bolt 33 beneath its head which fits within the circumferential groove 36 in the bolt, and the washer is permanently affixed to the boss 37 formed integral with the outer face of the inner jaw. The rail-engaging face of the shim block is provided with a projecting lip 38 along its lower edge, and depending from the bottom side of the block is a stop flange 39 which limits the inward movement of the shim block.

When it is desired to adjust the shim block 31 the bolt 33 is turned to move the block towards or from the rail head. By reason of the movement of the shim block in an upward direction, the lip 38 on the engaging face of the block will

directly contact the under side of the rail head, and thus establish a more firm connection between the rail clamp and rail head.

In practice it is found the adjustable rail clamp which has been provided for attaching the tie-spacer to the rail head permits the device to be more firmly and rigidly secured to rail heads of various sizes, thus greatly facilitating the utilization of the tie-spacer under all conditions. In the form of my invention more clearly shown in Fig. 4, shim blocks of varying sizes are selectively employed with the rail clamp and are readily interchangeable to adjust the clamp to fit rail heads of different sizes. In the form of my invention shown in Fig. 9, a single adjustable shim block is substituted for the series of blocks used in the other form, and inasmuch as the shim block may be adjusted after the clamp is applied to the rail head it enables the clamp to be more firmly secured in position.

It is to be understood that the form of my invention herein shown and described is to be taken as a preferred example of the same, and that certain changes in the shape, size, and arrangement of the parts may be made without departing from the spirit of the invention or the scope of the subjoined claims.

Having thus described my invention, I claim:

1. A rail clamp comprising an arm having inner and outer jaws for engaging opposite sides of a rail head, the lower edge of the outer jaw having an inwardly projecting lip for engaging the underside of the rail head, a removable shim block secured in a recess formed in the inner jaw having a projecting lip at its lower edge adapted to engage the underside of the rail head, the lip of the outer jaw and the lip of the shim block being normally spaced a distance less than the width of the rail head, said outer jaw having a V-notch above the lip to receive the lower edge of the rail head when applying the clamp to the rail head.
- 5 2. A rail clamp comprising an arm having inner and outer jaws for engaging opposite sides of a rail head, a socket formed in the inner jaw disposed at a downwardly inclined angle to the side of the rail head, a shim block slidably mounted in said socket having a projecting lip at its outer end adapted to engage the underside of the rail head, a bolt extending through the inner jaw having threaded engagement with said shim block for moving the same towards and from the rail head, and an inwardly projecting lip integral with the outer jaw adapted to engage the underside of the rail head.
